DRESS ENSEMBLE

Mamie Verrand, New York, N. Y.

Application December 20, 1950, Serial No. 13,503

Term of patent 3½ years

(Cl. D3—26)

To all whom it may concern:

Be it known that I, Mamie Verrand, a citizen of the United States, residing in New York city, in the county of New York and State of New York, have invented a new, original, and ornamental Design for a Dress Ensemble, of which the following is a specification, reference being had to the accompanying drawing, forming part thereof.

Fig. 1 is a front view of a dress ensemble showing my design.

Fig. 2 is a fragmentary rear view thereof.

Fig. 3 is a front view of the dress member of the ensemble shown in Fig. 1 and

Fig. 4 is the rear view thereof.

I claim:

The ornamental design for a dress ensemble, substantially as shown.

MAMIE VERRAND.
